WOODWORKING PLANE

Saul Shaler, Jackson Heights, N. Y.

Application April 2, 1948, Serial No. 18,602

4 Claims. (Cl. 145—13)

1

This invention is a woodworking plane which may be made almost entirely from sheet stock in an economical and efficient manner and yet produce a high class tool capable of fine work.

Heretofore plane stocks have been made either from wood or as metal castings. In either case they are relatively expensive and if they are dropped on the floor or other hard surface, they are very apt to be broken. However, when the stock of plane is made from sheet metal, such as sheet steel, of appropriate thickness, bent into the desired shape, the plane may be dropped upon a hard surface without any damage to the stock. Similarly bit clamps have heretofore been made either from wood or cast metal whereby they are also apt to become broken. The present invention provides for the manufacture of plane stocks and clamps embodying sheet metal stampings which may be dropped on a hard surface without damage thereto.

Likewise the pitch plate of the plane of the present invention, instead of being formed from a wood stock or cast integral with a cast stock, is in the form of a sheet metal stamping which in practice may be welded into the stock to form the throat of the plane.

In a similar manner other parts of the plane, which permit of their formation through the manipulation of sheet metal, are formed from such material and only those parts which may not be satisfactorily fabricated from sheet metal are otherwise constituted. As a result the primary parts of the plane of this invention may be made in quantity production with suitable dies to provide a tool of excellence and long life.

An important feature of the invention consists in the novel manner of forming and assembling the various parts of the plane to permit of economical and efficient manufacture and assembly and yet provide for all required adjustments in an easy and expeditious manner.

Features of the invention, other than those adverted to, will be apparent from the hereininafter detailed description and appended claims when read in conjunction with the accompanying drawings.

The accompanying drawing illustrates one practical embodiment of the invention, but the construction therein shown is to be understood as illustrative, only, and not as defining the limits of the invention.

Figure 1 is a plan view of the plane embodying the present invention.

Figure 2 is a central section on the line 2—2 of Figure 1.

2

Figure 3 shows certain parts of the plane dismantled and in perspective so that the structures of these individual parts may be clearly understood.

Figure 4 is a fragmental section on the line 4—4 of Figure 2.

Figure 5 is an enlarged fragmental section on the line 5—5 of Figure 1.

Figure 6 shows the way the blank of sheet metal, from which the stock is formed, is channeled or grooved to permit the blank to be bent to form substantially sharp edges along the sides of the stock.

The plane of this invention may be of any suitable type, but, for the purpose of illustration, I have shown the invention as incorporated in "Block Plane" construction. In manufacturing such a plane, the stock is formed from a flat sheet metal blank of appropriate thickness, preferably of the order of $\frac{1}{8}$ ", plus or minus.

In blanking out the stock, the central portion of the blank, which is to constitute the sole 1 of the stock, is punched to provide a slot or mouth 2, while the lateral portions of the blank 25 are shaped to form the upstanding side walls 3 of the stock. At the same time finger grip holes 4 are formed in the wall portions 3 and a perforation 4a is formed in the forward part of the sole portion to receive a rivet 5, by which the knob 6 may be subsequently attached. The blank is then longitudinally grooved or channeled along the line of meeting of the sole and side wall portions of the stock, as indicated at 7 in Figure 6, this channel being of V-shape and preferably extending a little more than half way through the thickness of the blank.

After the material has been blanked and channeled as stated, it is placed in a forming die which holds the sole portion of the blank flat and upsets the side wall portions 3 into substantially parallel but slight divergent relation to one another and substantially normal to the plane of the sole. The bending of the blank is accomplished along the lines of the channel 7, so that, when the sides are bent up as stated, both channels are substantially closed as shown in Figure 5. The advantage of channeling the blank is that, when bent as indicated in Figure 5, a very sharp edge may be produced, providing along the longitudinal edges of the stock, fairly sharp external angles, whereby the plane iron or bit which extends through the mouth of the sole, will be as close as possible to the exterior edges of the side walls 3 of the throat. This allows the plane to be used in the planing of rabbets and

other wood forms wherein the surfaces to be planed meet one another in an angle less than 180°.

In the plane of this invention, the element which underlies and supports the plane iron or bit 8 is also made from a sheet metal stamping in the form of the flanged pitch plate 9 shown in detail in Figure 3. It embodies a plate 9 provided along its lateral edges with depending wedge shaped flanges 10 and along its rear or upper edge with a depending flange 11 having two perforations 12 and 13. The plate 9 is also provided with a perforation 14 near its lower edge. This perforation is punched out in such manner as to displace the stock downwardly to form a boss 14a shown in Figure 2, to give greater thickness for threading the hole thus formed. This hole is adapted to receive the threaded post 35a of the plane. The hole 12 in the flange 11 is to receive the adjusting screw 15.

Between the hole 14 and the rear edge of the plate 9 is punched a rectangular hole 16 and the punching and forming die which carries out this operation forms some of the stock at the opposite sides of the hole 16 into two lugs 17 which are depressed about the thickness of the stock of the sheet metal from which the pitch plate is formed.

In bending the blank for the formation of the pitch plate and its flanges, said blank may be channeled in the same manner as the blank for the stock was channeled at 7, but this is not necessary as sharp edges are not required on the pitch plate.

The lugs 17 are adapted to act as retainers for an adjusting slide 18 shown in detail in Figure 3. The forward end of this adjusting slide is adapted to rest upon the lugs 17, as shown in Figure 2, and it is provided at its forward end with an upstanding nose 19 adapted to be received within a transverse slot 19a of the bit or plane iron 8. The rear end of said slide has a depending flange 20 provided with a punched and tapped hole 21 which, when the upper surface of the slide 18 is in face contacting relation with the under side of the pitch plate 9, is aligned with the hole 12 of the pitch plate, and the adjusting screw 15 is passed through the hole 12 and threaded into a tapped hole 21 of the slide. The adjusting screw 15 will hold the rear portion of the slide in engagement with the under side of the pitch plate, while the lugs 17 support the forward end of the slide and maintain the nose 19 in the hole 10 of the bit.

To preclude the slide from being inadvertently retracted so far as to disengage it from the lugs 17, said slide is provided with an upset stop 22 adapted to engage with the rear end of the hole 16 of the pitch plate before the forward edge of the slide is disengaged from the lugs 17. To preclude longitudinal movement of the adjusting screw 15, it is provided with a shoulder 24 bearing against a washer 23 embracing the knurled shank 15a on which the head 15b of the screw has a forced fit.

To laterally adjust the plane 9 or bit 8, a lever 25, shown in Figure 3, is secured to the rear of the flange 11 by a rivet 26 passed through a perforation 27 in said lever and through the perforation 13 of the flange and headed over as shown. This lever 25 has a central opening 28 in its power arm to straddle the head of the adjusting screw 15 with sufficient clearance to permit the lever 25 to be swung on its pivot to and fro about the axis of the rivet 26. The work arm 29 of the lever extends through a slot 30 in the bit, so that, when the tail piece 31 at the end

of the power arm of the latter is grasped and the lever is oscillated, the upper portion of the bit will be shifted laterally to square the cutting edge of the bit in the mouth 2 of the sole.

5 The pitch plate is adapted to be placed upon the upper surface of the sole between the side walls 3 and welded in place. This may be accomplished by three welds, one weld 31 being at the center of the forward edge and the other two 10 being at the opposite side walls, as indicated at 32. To facilitate accurate positioning of the pitch plate, in quantity production, each of the flanges 10 thereof is preferably provided with a projection 33 formed therein during the punching and 15 forming operation and complementary depressions are likewise formed in the inner surfaces of the side walls 3, whereby the mere act of bringing these projections into cooperation with the recesses, will properly position the pitch plate for 20 welding.

The bit clamp 34 is also die stamped from a flat sheet metal into substantially the form and shape shown. It is provided with a key hole slot 35 near its forward end for cooperation with a 25 post 35a and to the under side of its rear portion is riveted a fixed nut 36 in which operates the threaded shank 37 of the clamping screw. Formed integral with this screw is a hand wheel 38 and below the hand wheel projects the heel 39 of the screw, to bear against the upper surface of the bit 8. The bit clamp can be readily removed by loosening the clamping screw 37 through rotation of the hand wheel, whereupon it may be moved to position the large end of this 35 keyhole slot 35 in alignment with the head of the post 35a. The bit is thereby released and can be removed and replaced at will.

It will be noted that the rear edge of the mouth 2 is ground to the angle of the pitch plate, so that 40 the bit may be adjusted more readily with respect to the under surface of the sole and the forward edge of the mouth, to take shavings of the desired thickness. The holes 4 shown in Figure 2 provide 45 convenient means whereby the plane may be firmly gripped in use.

The foregoing detailed description sets forth the invention in its preferred practical form, but the invention is to be understood as fully commensurate with the appended claims.

50 Having thus fully described the invention, what I claim as new and desire to secure by Letters Patent is:

1. A woodworking plane comprising: a sheet metal stock having a sole with integral upturned 55 side walls, said sole having formed therein a transverse mouth, a pitch plate secured to the stock and interposed between said walls and extending in an upward inclined relation back from the mouth and provided with tapered depending lateral flanges resting on the sole and secured in 60 face contacting relation to the side walls of the stock, a headed post extending downwardly and threaded into a tapped hole in the pitch plate, a bit clamp apertured for detachable engagement 65 with said post and carrying on its under side a clamping screw for engagement with a bit resting upon the pitch plate beneath the bit clamp to detachably secure the bit to the pitch plate with the cutting edge of the bit extending through the 70 mouth of the sole, and a bit adjusting slide mounted for longitudinal movement against the under side of the pitch plate and having a projection extending upwardly through said plate to engage with a hole in the bit, said pitch plate being provided at its rear end with a depending 75

apertured flange, and an adjusting screw extending through the aperture in said flange and engaging with said slide to adjust the slide in a direction longitudinally of the pitch plate to correspondingly adjust the bit with respect to the mouth of the plane.

2. A woodworking plane comprising: a sheet metal stock having a sole with integral upturned side walls, said sole having formed therein a transverse mouth, a pitch plate rigidly secured to the stock between the side walls to support a plane bit with its cutting edge projecting through said mouth, said pitch plate having therein an opening with depressed parallel guide flanges along its lateral edges, a bit adjusting slide guided beneath said plate by said flanges and having a finger projecting upwardly through the opening in said plate into a hole in the bit, an adjusting screw coacting with the slide to move the latter toward and away from the mouth of the sole to longitudinally adjust the bit, and means for detachably engaging the bit while the same is in facial engagement with the pitch plate.

3. A woodworking plane comprising: a stock having a sole with integral upstanding side walls and a transverse mouth, a bit supporting pitch plate secured to the stock and positioned above the sole and between the side walls and inclined upwardly and rearwardly from the mouth and having an opening provided with depressed parallel guide flanges along the lateral edges of the opening, a bit adjusting slide guided in face contacting relation with the under side of the pitch plate by said flanges and having at its forward end an upstanding finger projecting upwardly through the opening in the plate into a hole in the bit, a depending lug at the rear end of the pitch plate, and an adjusting screw passing through said lug and coacting with the slide to move the slide and adjust the bit with respect to the mouth of the sole, and means for clamping the bit to the upper surface of the pitch plate.

4. A woodworking plane comprising: sheet metal stock having a sole and upstanding side walls at the lateral edges of the sole, a bit supporting sheet metal pitch plate positioned be-

tween the side walls and provided at its lateral edges with downwardly extending flanges resting upon the sole and in facial engagement with the inner surfaces of the side walls and secured thereto, said plate being provided at its rear edge with a depending lug and said plate having intermediate its ends an opening with depressed guide flanges along the opposite lateral edges thereof, a bit adjusting slide guided beneath said plate in said guides and having at its forward end an upstanding finger projecting through the opening in the plate and into a hole in the bit, an adjusting screw carried by the depending lug of said plate and threaded into the slide to effect adjustment of the slide when said adjusting screw is rotated, a clamping post mounted on and projecting above the pitch plate, a bit clamp detachably engaged near its forward end with said post and provided at its under side and near its rear end with a threaded boss, and a manually adjustable clamping screw in threaded engagement at one end with said boss and with its opposite end adapted to bear against the upper surface of a bit resting on said pitch plate.
